UNITED STATES PATENT OFFICE.

EVERETT G. GARRISON, OF NEWARK, NEW JERSEY.

DESIGN FOR A DISH.

No. 39,958.

Specification for Design.

Patented May 4, 1909.

Application filed March 5, 1909. Serial No. 481,551. Term of patent 14 years.

To all whom it may concern:

Be it known that I, EVERETT G. GARRISON, a citizen of the United States, residing in Newark, in the county of Essex and State of New Jersey, have invented a new, original, and ornamental Design for a Dish, of which the following is a specification, reference being had to the accompanying drawing, forming part thereof.

The figure is a perspective view of a dish showing my design.

I claim:

The ornamental design for a dish, as shown.

EVERETT G. GARRISON.
